UNITED STATES PATENT OFFICE.

OTTO OLSEN, OF BROOKLYN, NEW YORK.

FLOOR SCRAPER.

Application filed November 15, 1927. Serial No. 233,439.

My invention is designed particularly for use in connection with the mechanical floor scraper shown and described in my prior application for patent filed September 24, 5 1927, Serial No. 221,723, but is also capable of effective and convenient use as a floor scraper by itself, and in other mechanical floor scrapers designed to receive it.

In the embodiment of my floor scraper illustrated in my said prior application, the blade is held inclined transversely with respect to the direction of motion and downwardly and rearwardly with respect to the floor, and it consists of a flat plate of tool 10 steel which is clamped adjustably in the scraper with its lower transverse edge bent forwardly and downwardly and sharpened to act as the scraping blade proper.

My present improvement comprises, in its 20 present preferred embodiment, a flat metal plate to be clamped adjustably as described in the mechanical floor scraper or held tightly and correspondingly in the hand, said plate having its lower edge inclined upwardly and laterally with respect to its side edges and thus to the direction of motion and preferably beveled. On the back of said 25 plate across and registering with its lower edge is fixed the base of a triangular blade clamping block, whose diagonal face is thus 30 inclined to the back of the plate and forms a continuation of the beveled lower edge of the plate. To the clamping block is screwed an adjustable clamping plate, whose lower 35 edge coincides with those of the block and holding plate and between the jaws formed by the lower portions of the clamping block and clamping plate is clamped a detachable 40 scraping blade which is thus held and can be adjusted to the most effective position and can be made interchangeable of the highest quality tool steel, without the need of making its holding plate of such expensive metal.

45 In order that my invention may be fully understood, I shall first describe in detail the mode in which I at present prefer to carry my invention into practice and then particularly point out the invention in the 50 claims.

Reference is to be had to the accompanying drawings forming part of this application, in which like parts are designated by the same numbers in all the figures.

Figure 1 is a sectional side elevation illustrating a blade holder and blade embodying my present invention held in a mechanical floor scraper of the type illustrated in my said prior application. 55

Figure 2 is a rear view of the detachable 60 blade holder and blade.

Figure 3 is an enlarged cross-sectional view of the same.

In the drawings, 3 designates the blade holding body of the said mechanical floor 65 scraper, 4 its flat back and 5 its flat face, both inclined transversely with respect to the direction of travel, and downwardly and rearwardly with respect to the floor; 8 designates the blade holding plate seated against 70 the flat back 4, and 9 the clamping jaw by which the blade holding plate is held adjustably against the back 4, in a like transversely and longitudinally inclined position, all substantially as described in my said 75 prior application for patent.

Instead of making the plate 8 of tool steel and bending its lower edge forward to form the scraping blade proper, I in my present improvement cut the lower edge 19 of the 80 plate 8 at an inclination laterally and upwardly with respect to its side edges and bevel said lower edge 19 downwardly and forwardly, and I fix across the lower part 85 of said plate a clamping block 10 in this instance triangular in cross-section, having a diagonal clamping face 11, inclined downwardly and forwardly to coincide with the beveled edge which forms a continuation of the inclined face 11. On the clamping face 90 11, is secured adjustably a clamping plate 12 by screws 13 passing through apertures in the plate 12, into corresponding threaded screw holes 14 in the clamping block 10, and the lower edge of the clamping plate 12, 95 is inclined laterally and upwardly to coincide with the inclined beveled edge 19 of the plate 8.

Between the clamping block 10 and clamping plate 12 is held adjustably a detachable 100 scraping blade 15, with its lower sharpened edge inclined laterally and upwardly with respect to the side edges of the plate 8 to correspond with the lower edges 19 of the same and the clamping plate 12 and block 10. 105

The scraping blade 15 can thus be adjusted between the clamping plate and block to project therefrom the desired or most ef-

fective degree, and can easily be detached therefrom for resharpening or renewal.

It will be seen by inspection of Figure 1, that when the plate 8 is clamped in the mechanical floor scraper, as described in my said prior application, the scraping blade will be held at the most effective angle and projection with respect to the direction of motion and to the floor, and the lower edge 10 16 of the clamping plate 12 which is beveled, will act also as a guard to guide and limit the penetration of the blade 15.

The blade and blade holder can be used as a hand floor scraper, without the mechanical carrier, by holding it and moving it by hand at the same angle over the floor.

It is evident that specific details of the embodiment of my invention here illustrated

may be varied without departing from the boundaries of my invention as defined by the following claims.

I claim as my invention:

1. A floor scraper comprising a flexible blade holding plate thin in proportion to its length, and a scraping blade clamped immediately adjacent to and rigidly against and across the lower end of the holding plate so that its cutting edge projects forward of the front face of said plate.

2. A floor scraper in accord with claim 1 in which the bevelled face of the scraping blade is on the side farther from the holding blade.

In testimony whereof I affix my signature,

OTTO OLSEN.
